FILTER PAD

Herbert M. Gaarder, Chicago, Ill., assignor to
 Wilson & Company, a corporation of Delaware

Application September 25, 1936, Serial No. 102,577

4 Claims. (Cl. 183—45)

This invention relates to an improved air filter pad, and more particularly to a filter pad prepared of loosely aggregated fibrous material.

Air filters of the impingement type which re-
 5 move dirt, dust, pollen and bacteria from gases
 by impingement, as distinguished from a strain-
 ing process, have hitherto been customarily pre-
 pared and marketed in metal or cardboard con-
 tainers. These containers are normally of the
 10 size of the opening in which the filter is to be
 employed, and the filtering medium fits inside
 of them as closely as possible. Such covers are
 made as open as possible, but still decrease the
 filtering area about 20% or more, because they
 15 cover three-fourths of an inch to an inch at
 the edges and cover both the face and back of
 the filter to a considerable degree.

By means of the present invention, an over-
 sized pad is prepared with resilient edges, which
 20 compress against the sides of the filter frame and
 provide a dust-tight seal on all sides. At the
 same time, the edges of the filter are left un-
 covered, providing a maximum exposure of the
 25 surface.

The invention is illustrated in the drawing, in
 which—

Fig. 1 is a face view of a filter; and

Fig. 2 is a section of the line 2 in Fig. 1.

As illustrated in the drawing, the filter com-
 30 prises a mass of fibrous material 10 between a
 top screen 11 and a bottom screen 12, of very
 coarse mesh grid, the fibrous material extending
 beyond the edges, as indicated at 13. The top
 and bottom screens are joined and, at the same
 35 time, rigidly separated by pins or posts 14, which
 are welded to the lower screen and are provided
 with open hooks 15, which in assembling of the
 pad are passed over the upper grid and closed, as
 indicated at 16.

As an example of the invention, an air filter
 was produced by filling a square mold 20 $\frac{1}{4}$ inches
 on edge and about two inches thick with approxi-
 mately seven to eight ounces of hair. The hair
 is preferably hog hair, which may include minor
 45 proportions of uncurled hair, say 7 to 25% of
 small amounts, up to 10% of long hair, such as
 cattle hair, horse tail hair, or horse mane hair.
 The uncurled hair may be either intermixed with
 curled hair, or may be evenly distributed on one
 50 face of the filter, for example, the air exit face.
 The hair should be fluffed in order to provide
 proper density ratios, which should ordinarily
 be within the range of one-half to one and one-
 half ounces of hair per 100 cubic inches of pad,
 55 and preferably three-fourths to one and one-

fourth ounces. A thin pad, of course, is prefera-
 bly more dense than a thick one, and with shorter
 hair the density ranges may be somewhat higher.
 The loosely formed pad is then treated with an
 adhesive to bind the outer hairs firmly together, 5
 for example, by spraying the formed pad with an
 adhesive. The screens are then applied, one at
 the top and one at the bottom, and are anchored
 together. A preferred grid comprises openwork
 wires, for example, 14-gauge galvanized iron wire, 10
 spaced at approximately three-inch intervals and
 spot-welded at the junctions. For example, in a
 19 $\frac{1}{4}$ inch screen, the grid may be made up on
 five equally spaced wires of this type in each
 direction and are joined at the edges to a 12- 15
 gauge galvanized wire frame, slightly curved at
 the corners. The posts or pegs are preferably
 spotwelded to the frame at appropriate intervals
 about its edge, and the hooks are passed over
 20 the upper screen by compression of the pad and
 may then be clamped over the upper frame. With
 a 19 $\frac{1}{4}$ inch frame, as indicated, eight posts dis-
 tributed as indicated in Fig. 1 and made of 14-
 gauge wire are satisfactory. Posts may be sup-
 plied within the filter, if desired, particularly 25
 upon larger filters, but with filters up to 20 inches
 or even larger, such internal posts are not neces-
 sary for ordinary use.

After the screens have been applied and fas-
 tened together, the hairs may be coated with a 30
 tacky or dust-collecting material of the usual
 type, either by dipping or spraying. This opera-
 tion may be performed, if desired, before the
 grids are applied.

A pad prepared in this manner preferably is 35
 so made so that the hair extends one-quarter to
 three-quarters of an inch, and preferably about
 one-half inch, beyond the edges of the frame 17.
 Where the hair is resilient, as with hog hair, this
 provides a very effective dust seal when placed in 40
 a supporting frame, inasmuch as the frame 17 is
 only slightly smaller than the size of the frame
 in which the filter is to be placed. At the same
 time, the entire face of the filter is available
 45 for air filtering, increasing the available area
 about 20%, as compared with ordinary filters.
 The filter is also sufficiently rigid to permit tap-
 ping thereof face down to remove dust, without
 injury to the filter medium. The large mesh 50
 of the grids likewise affords practically no resist-
 ance to air passing through the filter. The posts
 shown are readily removable by opening of the
 hooks 16, and the grids may be removed from
 a dirt-filled pad and placed on a clean one.

While the filter has been described as being 55

of hair, other fibrous material, and particularly other fiber which is naturally or artificially resilient, may be employed.

The foregoing detailed description has been given for clearness of understanding only and no unnecessary limitations should be understood therefrom, but the appended claims should be construed as broadly as permissible, in view of the prior art.

10 I claim:

1. An air filter of the impingement type comprising a flat pad of loosely distributed resilient fibrous filtering material, a coarse mesh screen support of less cross-section than the pad, the edges of said pad extending substantially uniformly approximately one quarter to three quarters of an inch beyond the edges of the support, the resiliency of the fibers being such as to provide an edge seal having substantially the filtering capacity and low air resistance of the body of the filter, and said support being slightly small-

er and the pad slightly larger than the passageway for which the pad is intended.

2. A pad as set forth in claim 1 in which the outer fibers of the pad are bound firmly together with adhesive.

3. A pad as set forth in claim 1 in which the fiber is predominantly hog hair.

4. An air filter pad of the impingement type comprising a flat pad of loosely distributed resilient fibrous filtering material, a coarse mesh screen support of less cross-section than the pad, the edges of said pad extending substantially uniformly beyond the edges of the screen, the resiliency of the fibers and the width of said extension being such as to provide an edge seal having substantially the filtering capacity and low air resistance of the body of the filter, and said support being slightly smaller and the pad slightly larger than the passageway for which the pad is intended.
